UNITED STATES PATENT OFFICE.

WILLIAM P. BETTENDORF, OF DAVENPORT, IOWA.

UNDERFRAME FOR CARS.

No. 909,860.

Specification of Letters Patent. Patented Jan. 12, 1909.

Application filed May 15, 1907. Serial No. 373,815.

To all whom it may concern:

Be it known that I, WILLIAM P. BETTENDORF, a citizen of the United States, and a resident of Davenport, in the county of 5 Scott and State of Iowa, have invented certain new and useful Improvements in Underframes for Cars, of which the following is a clear, full, and exact description.

My invention relates to underframes for 10 cars, particularly those most if not all of the parts of which are made of metal.

The object of my invention is to simplify and reduce the cost of the underframe, while at the same time strengthening it, and increasing 15 its durability, and a further object is to transmit the stress and strain of the draft on the car from end to end thereof in the axial plane of the coupling. This I accomplish by the means hereinafter fully described and as particularly pointed out in 20 the claims.

In the drawings:—Figure 1 is a longitudinal central section through a portion of the underframe of a car embodying my improvements. Fig. 2 is a plan view of the same. Fig. 3 is an end view of the same. Fig. 4 is a transverse vertical section of a part of said underframe taken on dotted line 4, 4, Fig. 2. Fig. 5 is a similar transverse section thereof 30 taken on dotted line 5, 5, Fig. 2. Fig. 6 is a detail view showing one end of the center-sill drawn to a slightly larger scale. Fig. 7 is a view similar to that shown in Fig. 5 disclosing modified means for connecting the needle-beams to the side-sills.

My improved underframe comprises side-sills A, A, preferably made of channel-beams, and end-sills preferably made by bending the ends B, B, of said channel-beams inwardly 40 toward each other until they meet in a plane alining with the center of width of the car, at which point their ends are secured together by means of a suitable plate a. I prefer to bend these portions B, B, of said channel-beams so as to bulge the central portion of the end-sills longitudinally to form an advanced buffering portion B', and I floor over this projecting buffering portion B' by a floor-plate a', substantially as shown in the drawings.

The body-bolster G, preferably, consists of a single I-beam. In the event of my improvements being applied to a gondola car, the ends of this body-bolster are connected 55 to the lower ends of metal tee-stakes g, g,

which are riveted or otherwise secured to the inner surface of the side-sills and have their lower ends extending below the said side-sills and connected to the ends of the bolster G by plates g', g'. This manner of connecting 60 the ends of the body-bolster to the under-frame brings the upper flanged edge of the same below the plane of the upper flanged edges of the side-sills, and permits the use of longitudinally disposed strips h for the 65 floor of the body of the car. Between the corner-stakes of the body of the car the end-sills are reinforced by stakes H, that are, preferably, made of tee-metal shape, and have their lower end extend below the floor 70 and bent horizontally in the direction of the length of the car. These lower horizontal extensions H' of stakes H extend to and are connected by rivets or otherwise to the web of the body-bolster, and form braces between 75 said bolster and the end-sills and greatly strengthen and reinforce the construction of the ends of the underframe.

Extending lengthwise the car from end to end of the same is a single center-sill W, 80 which is, preferably, of a depth extending from the underside of the floor of the car to a suitable point below the lower flange of the body-bolster. Its web is provided with a suitable transverse opening G' through 85 which the body-bolster extends and said bolster is shearingly connected thereto by angles I, I, below its upper flanges and above the bolster opening, and by means of a U-shape centering-frame J the upper ends of 90 whose parallel branches are riveted to the lower flanges of the bolster. The bend of this centering-frame is formed into a suitable circular boss j that enters and is journaled in the usual bearings in the center of length 95 of the truck bolster.

In gondola cars of the type to which my improvements are applied, the plane of the line of draft is usually below the lower flange of the end-sill. In order, therefore, to accommodate the draft-gear in cars in which the single center-sill extends clear to said end-sills, as shown in Fig. 6, I provide the webs of the end portions of the center-sill with longitudinally elongated openings k. 100 In the crotch of the bifurcations thus formed I introduce a frame-work x, which is, preferably, U-shape, or rectangular, substantially as shown, and provide the same with a transverse rectangular opening. 110

In cars where the single center-sill extends over the body-bolsters, but does not extend quite to the end-sills, I suitably secure to each end of said center-sill a frame-work L, 5 preferably, made of cast steel. The portion of this frame-work secured to the extremity of the center-sill is about the same height thereas, but its lower edge is, about midway between the said extremities and end-sills, 10 curved upwards to about the plane of the lower edge of the end-sill to which its (said frame-works) end is secured in a plane about the draft gear. In the rear portion of frame-work L adjacent to the center-sill, a trans- 15 verse rectangular opening is made, and the buffer-springs m are placed in this opening, and bear against the usual spring follower-plates (not shown). The shank of the coupler K extends under the end-sill and is 20 supported by a stirrup K' of the usual construction secured to and depending from said end-sill, and its rear portion has secured thereto in front of the shoulder (made by reducing the height of the frame-work L), 25 the straps M, which latter extend rearwardly on either side of the spring m and have their rear portions N constructed so as to engage the aforesaid spring buffer-plates, in the usual manner.

30 The construction of the straps M and the rear portion N thereof, and the arrangement of the buffer-spring and devices for operatively connecting the same to said straps, are the same in the construction shown in Fig. 6 of the drawings as in Fig. 1.

Between the body-bolsters the single I-beam center-sill is provided between its upper and lower flanges with openings v through which transverse needle-beams V 40 extend, which latter, preferably, have their ends connected to the lower extensions of the side-stakes n, n, of the car-body, by plates o, o, in the same manner as do stakes g, g. In addition to these stakes the car- 45 body is, preferably, provided with a series of side-stakes P, which alternate therewith and have their lower ends extend down below the floor of the car and bent towards and secured to the adjacent side of the center- 50 sill by riveting or otherwise, substantially as shown. The lower portions of the intermediate side-stakes P form braces R between the center-sill and the side-sills and greatly add to the transverse strength of the under- 55 frame. The lower and upper flanges of the needle-beams are shearingly secured to the single center-sill by means of brackets r, r, and s, s, substantially as shown, but it is obvious that these brackets may be dispensed with 60 if desired.

I do not desire to be confined to the use of the metal-plates a and o for securing the ends of the body-bolster and the ends of the needle-beams to the side-sills of the under- 65 frame, but may, particularly when the stakes

of the body are made of wood, connect said ends to cast metal sockets S that are secured to the inner surface of the side-sills, and are adapted to receive the lower ends of the wooden-stakes T.

What I claim as new is:—

1. An underframe for cars comprising suitable end-sills, body-bolsters, and a center-sill consisting of a single rolled metal beam extending continuously from end to end of the car past said bolsters to points adjacent to said end-sills and connected thereto and having openings between its upper and lower edges through which said bolsters pass.

2. An underframe for cars comprising suitable end-sills, body-bolsters, and a center-sill consisting of a single rolled metal I-beam extending continuously from end to end of the car past said bolsters to points adjacent to said end-sills and having openings between its upper and lower edges through which said bolsters pass.

3. An underframe for cars comprising suitable end-sills, body-bolsters, and a center-sill consisting of a single rolled metal beam extending continuously from end to end of the car past said bolsters to points adjacent to said end-sills and having openings therein through which said bolsters pass.

4. An underframe for cars comprising suitable end-sills, side-sills, body-bolsters, needle-beams, and a center-sill consisting of a single rolled metal beam extending continuously from one end to the other of the car past said bolsters to points adjacent to said end-sills, and having openings therein for the passage therethrough of said bolsters and needle-beams.

5. An underframe for cars comprising suitable end-sills, body-bolsters, and a center-sill consisting of a single rolled metal beam of greater depth than said end-sills and extending continuously from end to end of the car past said bolsters to points adjacent to the same and having openings between its upper and lower edges through which said bolsters pass.

6. An underframe for cars comprising suitable end-sills, body-bolsters, and a center-sill consisting of a single rolled metal beam extending continuously from end to end of the car to points adjacent to said end-sills and having longitudinally elongated openings in its ends.

7. An underframe for cars comprising suitable end-sills, body-bolsters, and a center-sill consisting of a single rolled metal beam of greater depth than said end-sills and extending continuously from end to end of the car to points adjacent to the same and having longitudinally elongated openings in its ends.

8. An underframe for cars comprising suitable end-sills, body-bolsters, a center-sill consisting of a single metal beam the ends of which extend past said bolsters, and a frame-

work for draft-rigging secured to said ends between said bolsters and end-sills.

9. An underframe for cars comprising suitable end-sills, body-bolsters, and a single center-sill through which said bolsters pass, which center-sill consists of a rolled metal beam extending from end to end of the car to points adjacent to said end-sills, and having the web of its ends below the plane of the end-sills bifurcated horizontally.

10. An underframe for cars comprising suitable end-sills, body-bolsters, a single center-sill consisting of a rolled metal beam, through which said bolsters pass, and the ends of which extend past said bolsters, and a suitable cast steel framework connected to and equally disposed on both sides of each end of said beam.

11. An underframe for cars comprising suitable end-sills, body-bolsters, a single center-sill through which said bolsters pass, said center-sill consisting of a rolled metal beam extending continuously from end to end of the car to points adjacent to said end-sills, and draft-rigging frames supported by and equally disposed on both sides of each end of said center-sill.

12. An underframe for cars comprising suitable end-sills, body-bolsters, a center-sill consisting of a single rolled metal beam extending continuously from end to end of the car to points adjacent to said end-sills and having longitudinally elongated openings in its ends, and draft-rigging frames inserted and secured in said longitudinally elongated end opening.

13. An underframe for cars comprising suitable end-sills, body-bolsters, a center-sill consisting of a single metal beam the ends of which extend past said bolsters, and a suitable frame-work connected to said ends having a transverse opening therein.

14. An underframe for cars comprising suitable end-sills, body-bolsters, a center-sill consisting of a single rolled metal beam extending continuously from end to end of the car to points adjacent to said end-sills having its ends below the plane of the end-sills bifurcated, and draft-rigging frames inserted and secured between said bifurcations.

15. An underframe for cars comprising suitable end-sills, body-bolsters; and a center-sill consisting of a single rolled metal beam extending continuously from end to end of the car to points adjacent to said end-sills having longitudinally elongated openings in its ends, and having openings therein through which said bolsters pass.

16. An underframe for cars comprising suitable end-sills, body-bolsters, needle-beams, and a center-sill consisting of a single rolled metal beam extending continuously from end to end of the car to points adjacent to said end-sills having longitudinally elongated openings in its ends, and openings

therein through which said bolsters and needle-beams pass.

17. An underframe for cars comprising suitable end-sills, body-bolsters, a center-sill consisting of a metal beam having an opening therein through which said bolsters extend, and end-posts the lower ends of which are suitably secured to said end-sills and extended in a longitudinal direction and secured to said body-bolsters.

18. An underframe for cars comprising suitable end-sills, side-sills, body-bolsters disposed in a plane below said side-sills, means for securing the same to said side-sills, and a center-sill consisting of a metal beam having openings therein through which said bolsters extend.

19. An underframe for cars comprising suitable end-sills, side-sills, body-bolsters disposed in a plane below said side-sills, plates for securing the same to said side-sills, and center-sill consisting of a metal beam having openings therein through which said bolsters extend.

20. An underframe for cars comprising suitable end-sills, body-bolsters disposed in a plane below said side-sills, needle-beams, a center-sill consisting of a metal beam having openings therein through which said bolsters and needle-beams extend, and plates securing the ends of said bolsters and needle-beams to said side-sills.

21. An underframe for cars comprising suitable end-sills, body-bolsters disposed in a plane below said side-sills, needle-beams, a center-sill consisting of a metal beam of a depth exceeding that of said bolsters and having openings therein through which said bolsters and needle-beams extend, and plates securing the ends of said bolsters and needle-beams to said side-sills.

22. An underframe for cars comprising suitable end-sills, body-bolsters disposed in a plane below said side-sills, needle-beams, a center-sill consisting of a metal beam of a depth extending down from the floor of the car to below the lower edge of said bolsters and having openings therein through which said bolsters and needle-beams extend, and plates securing the ends of said bolsters and needle-beams to said side-sills.

23. An underframe for cars comprising suitable end-sills, body-bolsters, a center-sill consisting of a single metal beam extending from end to end of the car having an opening therein through which said bolsters extend, and end-posts the lower ends of which are suitably secured to said end-sills and extended in a longitudinal direction and secured to said body-bolsters.

24. An underframe for cars comprising suitable end-sills, side-sills, body-bolsters disposed in a plane below said side-sills, means for securing the same to said side-sills, and center-sill consisting of a single

metal beam extending from end to end of the car having openings therein through which said bolsters extend.

25. An underframe for cars comprising suitable end-sills, side-sills, body-bolsters disposed in a plane below said side-sills, plates for securing the same to said side-sills, and center-sill consisting of a single metal beam extending from end to end of the car 10 having openings therein through which said bolsters extend.

26. An underframe for cars comprising suitable end-sills, body-bolsters disposed in a plane below said side-sills, needle-beams, a center-sill consisting of a single metal beam 15 extending from end to end of the car having openings therein through which said bolsters and needle-beams extend, and plates securing the ends of said bolsters and needle-beams to said side-sills.

27. An underframe for cars comprising suitable end-sills, body-bolsters disposed in a plane below said side-sills, needle-beams, a center-sill consisting of a single metal beam 25 extending from end to end of the car of a depth exceeding that of said bolsters and having openings therein through which said bolsters and needle-beams extend, and plates securing the ends of said bolsters and needle-beams to said side-sills.

28. An underframe for cars comprising suitable end-sills, body-bolsters disposed in a plane below said side-sills, needle-beams, a center-sill consisting of a single metal beam 35 extending from end to end of the car which is of a depth extending down from the floor of the car to below the lower edge of said bolsters and having openings therein through which said bolsters and needle-beams extend, and plates securing the ends of said bolsters and needle-beams to said side-sills.

29. An underframe for cars comprising suitable end-sills, body-bolsters, a center-sill consisting of a metal beam having its 45 ends bifurcated and having an opening therein through which said bolsters extend, and end-posts the lower ends of which are suitably secured to said end-sills and extended in a longitudinal direction and secured to said body-bolsters.

30. An underframe for cars comprising suitable end-sills, body-bolsters, a center-sill consisting of a metal beam having its ends bifurcated and having an opening therein 55 through which said bolsters extend, draft rigging frame inserted and secured between said bifurcations, and end-posts the lower ends of which are suitably secured to said end-sills and extended in a longitudinal direction and secured to said body-bolsters.

31. An underframe for cars comprising suitable end-sills, side-sills, body-bolsters disposed in a plane below said side-sills, means for securing the same to said side-sills and center-sill consisting of a metal 65

beam having its ends bifurcated and having openings therein through which said bolsters extend.

32. An underframe for cars comprising suitable end-sills, side-sills, body-bolsters 70 disposed in a plane below said side-sills, means for securing the same to said side-sills and center-sill consisting of a metal beam having its ends bifurcated and having openings therein through which said bolsters 75 extend and draft rigging frame inserted and secured between said bifurcations.

33. An underframe for cars comprising suitable end-sills, body-bolsters disposed in a plane below said side-sills, needle-beams, a center-sill consisting of a metal beam having 80 its ends bifurcated and having openings therein through which said bolsters and needle-beams extend, and plates securing the ends of said bolsters and needle-beams 85 to said side-sills.

34. An under-frame for cars comprising suitable end-sills, body-bolsters disposed in a plane below said side-sills, needle-beams, a center-sill consisting of a metal beam having 90 its ends bifurcated and having openings therein through which said bolsters and needle-beams extend, and plates securing the ends of said bolsters and needle-beams to said side-sills and draft rigging frame inserted 95 and secured between said bifurcations.

35. An underframe for cars comprising suitable end-sills, body-bolsters disposed in a plane below said side-sills, needle-beams, a center-sill consisting of a metal beam the 100 ends of which are bifurcated, which is of a depth exceeding that of said bolsters and having openings therein through which said bolsters and needle-beams extend, and plates securing the ends of said bolsters and needle-beams to said side-sills. 105

36. An underframe for cars comprising suitable end-sills, body-bolsters, a center-sill consisting of a single metal beam extending from end to end of the car having its ends bifurcated and having an opening therein 110 through which said bolsters extend, and end-posts the lower ends of which are suitably secured to said end-sills and extended in a longitudinal direction and secured to said body-bolsters. 115

37. An underframe for cars comprising suitable end-sills, side-sills, body-bolsters disposed in a plane below said side-sills, means for securing the same to said side-sills, and center-sill consisting of a single metal beam extending from end to end of the car having its ends bifurcated and having 120 openings therein through which said bolsters extend. 125

38. An underframe for cars comprising suitable end-sills, side-sills, body-bolsters disposed in a plane below said side-sills, plates for securing the same to said side-sills, 130

and center-sill consisting of a single metal beam extending from end to end of the car having its ends bifurcated and having openings therein through which said bolsters extend.

39. An underframe for cars comprising suitable end-sills, body-bolsters disposed in a plane below said side-sills, needle-beams, a center-sill consisting of a single metal beam 10 extending from end to end of the car having its ends bifurcated and having openings therein through which said bolsters and needle-beams extend, and plates securing the ends of said bolsters and needle-beams to said side-sills.

40. An underframe for cars comprising suitable end-sills, body-bolsters disposed in a plane below said side-sills, needle-beams, a center-sill consisting of a single metal beam 20 extending from end to end of the car having its ends bifurcated and which is of a depth exceeding that of said bolsters and having openings therein through which said bolsters and needle-beams extend, and plates 25 securing the ends of said bolsters and needle-beams to said side-sills.

41. An underframe for cars comprising suitable end-sills, body-bolsters, a single center-sill consisting of a metal beam, the web of 30 the ends of which are transversely bifurcated and extend past said bolsters to said end-sills to which they are suitably connected, and a draft-rigging frame secured in the bifurcated ends of said beam between 35 said bolsters and said end-sills.

42. An underframe for cars comprising suitable end-sills, body-bolsters, a single center-sill consisting of a metal beam the ends of which extend past said bolsters to said 40 end-sills to which they are suitably connected and have transverse openings therein back from the said ends in the web between its upper and lower flanges through which 45 said bolsters pass, and a draft-rigging frame secured in said openings between said bolsters and end-sills.

43. An underframe for cars comprising suitable end-sills, body-bolsters each of 50 which are continuous from side-frame to side-frame, a single center-sill consisting of a metal beam the ends of which extend past said bolsters to said end-sills to which they are suitably connected and have transverse openings back from the said ends in the web 55 between its upper and lower flanges through which said bolsters pass, and a draft rigging frame secured in said openings between said bolsters and end-sills.

44. In an underframe for cars a single 60 center-sill, consisting of an integral metal beam extending from end to end of the car past the body-bolsters, and having transverse openings in the web thereof between the bolsters and car ends and mediate the

flanges of said beam, and needle beams ex- 65 tending through the openings in said center-sill.

45. An underframe for cars comprising side-sills, end-sills, body-bolsters and a single center-sill consisting of a continuous 70 metal beam extending from end to end of the car and having a portion of the web below the plane of the end-sill cut away back from its ends to a point mediate said ends and the body-bolster.

46. An underframe for cars comprising suitable end-sills, body-bolsters each consisting of a continuous member extending from side to side of the car-body, and a single center-sill consisting of a metal beam of 80 a depth exceeding that of said end-sills and bolsters and extending continuously from end to end of the car past said bolsters to a point adjacent to said ends.

47. An underframe for cars comprising 85 suitable end-sills, body-bolsters each consisting of a single continuous member extending from side to side of the car-body, and a single center-sill consisting of a metal beam of a depth exceeding that of said end- 90 sills and said bolsters and extending continuously from end to end of the car past said bolsters to a point adjacent to said ends.

48. An underframe for cars comprising suitable end-sills, body-bolsters each consisting of a continuous member extending from side to side of the car-body, and a single center-sill consisting of a metal beam of a depth exceeding that of said end-sills and 95 said bolsters and extending continuously from end to end of the car past said bolsters to a point adjacent to said ends and having transverse openings in the web thereof below the plane of said end-sills through which 100 said bolsters pass.

49. An underframe for cars comprising a center sill which between the body-bolsters of the car and the end-sills consists of a single metal beam, and a supporting-frame for draft-rigging secured thereto and having its 110 sides projecting transversely beyond the sides of the web of said beam.

50. An underframe for cars comprising a center-sill, which between the body-bolsters of the car and the end-sills thereof consist of a single metal beam which is provided with a transverse opening, and a supporting-frame for draft-rigging secured in said opening and having its sides projecting on each side of the web of said metal beam.

In testimony whereof I have hereunto set my hand and seal this 25th day of April, 1907.
